UNITED STATES PATENT OFFICE.

HAROLD L. BLANCHARD, OF MILLBURY, MASSACHUSETTS, ASSIGNOR TO CROMPTON & KNOWLES LOOM WORKS, OF WORCESTER, MASSACHUSETTS, A CORPORATION OF MASSACHUSETTS.

INTERMITTENT FEELER IN TRANSFERRER.

Application filed October 26, 1925. Serial No. 64,756.

This invention relates to weft detecting mechanism for looms and it is the principal object of the invention to provide means for rendering intermittently operative the type of weft detector which is mounted in a regularly reciprocating transerrer arm.

In Patent No. 1,372,316 there is shown a multi-color weft replenishing mechanism having a regularly reciprocating transerrer arm which is moved down on detecting beats of the lay while the shuttle is under the magazine. A weft detector is mounted on the transerrer and detects the condition of yarn in the active shuttle on the downward stroke of the transerrer arm. By means of additional mechanism the transerrer is effective on its upward stroke to indicate weft exhaustion and the magazine is set for replenishment on a subsequent pick.

In this type of detector it is found that when very fine yarn is being woven the detector is moved downwardly to strike the surface of the yarn a great number of times before replenishment is called for resulting in fraying of the yarn and it is a further object of my invention to hold the detecting surface out of contact with the yarn except at periodic intervals so as to avoid undue wear.

Patent No. 1,551,219 relates to the same general type of detector and shows a yielding actuator arm which engages one end of the lever on the transerrer on which the detector is mounted. It is a more particular object of my invention to provide for holding this actuating arm inoperative while an abundance of yarn is present but rendering the same operative on each detecting beat of the lay when a small amount of weft remains on the bobbin.

Immediately after indication of exhaustion a shuttle might become inactive but the transerrer must continue to receive its periodic descents to be ready to replenish the depleted shuttle when it again becomes active. In order that the detector will not strike the yarn on its regular descents with the transerrer it is so held as normally to be above the surface of a full bobbin and will not engage the surface to be detected unless moved by the actuator arm.

With these and other objects in view which will appear as the description proceeds, my invention resides in the combination and ar-

rangement of parts hereinafter described 55 and set forth in the claims.

In the accompanying drawings wherein I have shown the form of actuating arm illustrated in the second patent above mentioned, —

Fig. 1 is an end elevation taken from the interior of the loom of a multi-color weft replenishing mechanism having my invention applied thereto,

Fig. 2 is an enlarged section on line 2—2 65 of Fig. 1 showing the detector in normal position when the transerrer arm is at the bottom of its stroke,

Fig. 3 is a fragmentary view looking in the direction of arrow 3, Fig. 2 and showing 70 the relation of the actuating arm and the detector carrying lever when the amount of weft present is small enough to require detection on each alternate beat of the lay,

Fig. 4 is a view similar to Fig. 3 but with 75 the actuating arm shown locked in inoperative positive, a condition desirable when an abundance of yarn is present in the active shuttle,

Fig. 5 is top plan view looking in the 80 direction of arrow 5, Fig. 1,

Fig. 6 is a vertical section on line 6—6 of Fig. 1, and

Fig. 7 is a fragmentary detail view showing 85 a portion of the actuator arm and holding detent when said arm is locked in inoperative position as shown in dotted lines in Fig. 1 and full lines in Fig. 4.

Referring to the drawings it will be seen that I have provided a magazine frame 10 having a transerrer arm 11 pivotally mounted on a stud 12 secured to the frame in any approved manner and receiving a downward movement on detecting picks by a suitably actuated rod 13 attached thereto. Vertical 90 slides 14 are controlled by a longitudinally and angularly movable color slide 15 which is moved longitudinally by a bell crank lever 16 pivoted at 17 to a fixed part of the structure and actuated by a rod 18 connected with the pattern mechanism or box motion so as to keep the color slide 15 in step with the active shuttle.

A stud 19 is fixed to the magazine and has loosely mounted thereon bell crank lever 20 105 the horizontal arm of which is connected by means of a link 21 to the color slide 15 to give the latter an upward movement every alter-

nate beat of the lay while the active shuttle is on the opposite side of the loom. The depending arm of lever 20 is provided with a cam face 22 which cooperates with a plunger 23 slidably mounted in a portion of the trans-
ferrer arm which extends substantially parallel to the shuttle.

By referring to Fig. 2 it will be seen that a lever 24 is pivoted as at 25 to the trans-
ferrer arm and has pivotally mounted on one end thereof as at 26 a detector arm 27 the detecting surface 28 of which is offset vertically from the pivot 26. A rod 29 is interposed between the detector arm 27 and the plunger 23 and is surrounded by a coil spring 30 interposed between a shoulder on the rod and the trans-
ferrer arm. Said spring 30 serves to hold the detector arm in the normal position shown in Fig. 2, ad-
justing screw 31 being interposed between the detector arm and the lever 24 to limit outward movement of the detector under influence of spring 30.

The other end of arm 24 is provided with an offset lug 32 seen in Figs. 1, 2, 3, and 4 and is so positioned as to have contact with an actuating arm 33 as the trans-
ferrer nears the bottom of its motion, provided said arm 33 is in raised position. A screw 34 extends through the arm 24 and engages a part of the trans-
ferrer arm, the lever 24 being held yieldingly in the position shown in Fig. 2 by the spring 30. Said yielding arm 33 is pivoted as at 35 to a fixed part of the re-
plenishing mechanism and is connected as at 36 to an upwardly extending rod 37 which extends through a boss 38 on the frame 10. Upper and lower collars 39 and 40, respectively, are secured to the rod 37 and spring 41 is interposed between the boss 38 and collar 39 to hold said rod and actuating arm yieldingly in raised position. Collar 40 limits upward movement of the actuating arm under influence of spring 41. Rod 37 is formed with teeth 42 and 43, respectively, which define a notch 44. A plunger 45 is guided in fixed bosses 46 and is held in contact with one or both of said teeth by spring 47.

The rear end of the arm 33 is offset and pivotally connected as at 48 to an upwardly extending link 49 which has a slot 50 receiving a pin 51 on pawl 52 pivoted on an arm 53 at 54. Said arm 53 is secured to the color slide and moves angularly therewith to give the pawl 52 a back and forth motion and also moves said pawl so that the same is brought into operative relationship with respect to one or another of a plurality of ratchet wheels 55, 56, 57, and 58, one ratchet wheel being provided for each color of the maga-
zine. Said ratchet wheels are the same and are freely rotatable upon a stud 59 secured to and extending rearwardly from the frame 10. Each ratchet is provided with a series

of teeth 60 and one high tooth 61. A spring 62 may be provided for each ratchet wheel to prevent retrograde movement. Secured to and extending rearwardly from frame 10 is an arm 63 on which the actuating pawl 52 may rest. Said arm 63 is provided with a plurality of humps 64 (Fig. 1) located between the ratchet wheels and so disposed that as the color slide 15 moves longitudinally the pawl will be raised. The stroke of the pawl 52 is somewhat greater than the distance between adjacent teeth and the pawl is formed substantially as shown in Fig. 6 to allow the high tooth 61 to lie thereunder when said pawl is acting on the tooth immediately in front of the high tooth.

Assuming that the active shuttle has very little yarn left therein lug 32 will be engaged by actuator arm 33 as the trans-
ferrer arm, descends and the detector 27 will be moved against the yarn W of the bobbin B. Under these conditions the actuator arm 33 remains at rest, being held in raised position by the combined action of springs 41 and 47 and detector 27 has a detecting movement on alternate picks.

When the weft is depleted detector 27 will slide along the bobbin to move plunger 23 to the dotted line position shown in Fig. 1 to set the magazine as set forth in the afore-
said patents. When the full bobbin is in the active shuttle detector 27 will not be able to move down very far and lug 32 will receive a correspondingly large motion to de-
press arm 33 and cause plunger 45 to enter notch 44 and hold said actuating arm 33 down as shown in dotted lines in Fig. 1. As plunger 45 enters notch 44 arm 33 is given an additional downward motion and on sub-
sequent picks is too low to engage lug 32 to move detector 27 against the yarn. Said detector is therefore held out of action as long as arm 33 is depressed.

The actuating arm 33 is periodically re-
stored to actuating position by the action of the ratchet wheels and pawl 52. On every non-detecting pick the color slide 15 will be rocked in a manner as set forth in the afore-
said patents to give said pawl a movement to the right as shown in Fig. 6 and will move the ratchet corresponding to the active shuttle ahead with a step by step motion. The large tooth 61 will ultimately come under the pawl as shown in Fig. 6 and on the re-
turn movement the pawl will be raised and pin 51 will lower link 49 to reset the actuating arm to the full line position shown in Fig. 1. It is to be understood that when arm 33 is down pin 51 rests in the bottom of slot 50. If an abundance of yarn is present the arm 33 will again be moved out of action, but if a small amount of yarn is in the shuttle, the detector 27 will move down far enough so that plunger 45 will not be

able to enter notch 44 and the detector will therefore be operative on all detecting picks.

- If a full shuttle is to be followed in action by one nearly exhausted, it will be necessary 5 to restore the arm 33 to operative position in order that more frequent detection of the depleted shuttle may occur. This result is accomplished by the humps 64 on the arm 63. As the active shuttle changes there will 10 be an endwise movement of the color slide and the pawl, which moves with the slide, rises as it passes over one or more of the humps. If the arm 33 is down, the rising of the pawl will restore it to normal and if 15 the said arm is already up, pin 51 will move down in slot 50 without communicating motion to arm 33 because of the fact that under this latter condition pin 51 will be in the top of slot 50.
- 20 The use of a series of ratchet wheels, one for each shuttle, to measure the picks laid by each shuttle is shown in co-pending application No. 739,713 and forms no part of my invention, except that the pawl 52 serves 25 the double function of actuating the ratchets and also giving the indication to reset arm 33.

My purpose in providing two spring devices each of which is effective to raise actuator arm 33, namely, the spring 41 and the spring plunger 45, is to permit the use 30 of the mechanism for weaving with relatively heavy yarn. When such a fabric is being woven there is no necessity for rendering the detector intermittent and under such conditions the plunger 45 will be moved to the left as shown in Fig. 1 and a cotter pin or other suitable holding device passed through the hole 65 formed in said plunger and so placed as to hold the same away from the teeth 42 and 43 so that the spring will 35 on all detecting picks operate to hold the actuator arm 33 raised. I do not wish to be limited to the use of both of these devices 40 inasmuch as the cam action between the tooth 42 and the plunger 45 would serve to raise the actuator arm if spring 41 were not present provided of course that the connector 37 passed through its guide 38.

50 From the foregoing it will be seen that I have provided means for periodically disabling the actuator arm 33 to render the detector in the transerrer inoperative when an abundance of weft is present but that 55 when the supply of weft is depleted the actuator arm will become operative and detector arm 27 will be moved down on every detecting beat of the lay. Also it will be seen that the actuator arm 33 is returned to normal position every time there is a change in the active shuttle. Furthermore, it will be seen that the detector arm 27 is so positioned as to be above a full supply of weft 60 when the transerrer arm is in its lowest position so that when the actuator arm 33

is in inoperative position no portion of the detecting mechanism will engage the bobbin.

Having thus described my invention it will be apparent that changes and modifications may be made therein by those skilled 70 in the art without departing from the spirit and scope of the invention, and I do not wish to be limited to the details herein disclosed but what I claim is:

1. In a weft detecting mechanism for 75 looms, a weft detector, a support for said detector to move the latter toward the weft supply on detecting beats of the loom, means normally at rest to be operatively connected to the detector as the latter is moved toward the weft supply and operative when so connected to move the detector into contact with the weft supply, and a device to hold 80 said means out of position to be operatively connected with the detector when a relatively large amount of yarn is present.

2. In a weft detecting mechanism for 85 looms, a weft detector, a support for said detector to move the latter toward the weft supply on detecting beats of the loom, means 90 normally at rest to be operatively connected to the detector as the latter is moved toward the weft supply and operative when so connected to move the detector into contact with the weft supply, a device to hold said means 95 out of position to be operatively connected with the detector when a relatively large amount of yarn is present, and mechanism to restore said means to the position where the same will be operatively connected to 100 the detector.

3. In a weft replenishing loom having a transerrer arm movable at regular intervals toward the supply of weft, a weft detector mounted on the transerrer arm, 105 means to actuate the detector as the transerrer arm moves toward the supply of weft, and a device to render said means inoperative to actuate the detector when a relatively large amount of weft is present. 110

4. In a weft replenishing loom having a transerrer arm movable at regular intervals toward the supply of weft, a weft detector mounted on the transerrer arm, 115 means to actuate the detector as the transerrer arm moves toward the supply of weft, a device to render said means inoperative to actuate the detector when a relatively large amount of weft is present, and mechanism to return said means to operative position with 120 respect to the detector.

5. In a weft replenishing loom having a transerrer arm movable at regular intervals toward the supply of weft, a weft detector mounted on the transerrer arm and 125 movable toward the supply of weft with the transerrer arm, an actuator for the detector to render the detector operative to detect when said actuator is in operative position with respect to the detector, and a 130

device to move said actuator out of operative relationship with respect to the detector when a relatively large amount of weft is present.

6. In a weft replenishing loom having a transerrer arm movable at regular intervals toward the supply of weft, a weft detector mounted on the transerrer arm and movable toward the supply of weft with the transerrer arm, an actuator for the detector to render the detector operative to detect when said actuator is in operative position with respect to the detector, a device under control of the weft to initiate movement of said actuator to a position out of operative relationship with respect to the detector when a relatively large amount of weft is present, additional means to complete the movement of said actuator to a position out of operative relation with the detector, and mechanism to return said actuator to operative relationship with respect to the detector.

7. In a weft replenishing loom having a transerrer arm movable at regular intervals toward the supply of weft, a detector mounted on the transerrer arm and movable toward the weft supply as the transerrer arm moves down but held normally out of contact with the weft supply when the transerrer is nearest said supply, an actuator to move the detector against the supply of weft, and means to render said actuator ineffective to actuate the detector when a relatively large supply of weft is present.

8. In a weft replenishing loom having a weft supply to be detected and a transerrer movable at periodic intervals toward the weft supply, a weft detector carried by the transerrer and movable therewith toward the weft supply, and means controlled by the weft to render said detector operative to detect every detecting beat of the loom when a relatively small amount of yarn is present and to detect at less frequent intervals when a relatively large amount of yarn is present.

9. In a weft detector for multi-shuttle looms, a weft detector, a support for said detector to move the latter toward the weft supply on each detecting beat of the loom, means to be operatively connected to the detector when the latter approaches the weft supply and operative when so connected to

move the detector against the weft supply, a device to hold said means out of position to be operatively connected to the detector when a relatively large amount of weft is present, and a plurality of controlling elements each effective to act on said device to cause the same to restore the means to operative position with respect to the detector, said controlling elements each being effective to act on the device after a predetermined number of beats of the loom only.

10. In a multi-color weft replenishing mechanism having a transerrer arm movable toward the weft supply on every detecting beat of the loom, a weft detector mounted on the transerrer arm and movable therewith toward the weft supply, a support for said detector to move the latter toward the weft supply on each detecting beat of the loom, means to be operatively connected to the detector when the latter approaches the weft supply and operative when so connected to move the detector against the weft supply, a device to hold said means out of position to be operatively connected to the detector when a relatively large amount of weft is present, and a plurality of controlling elements each effective to act on said device to cause the same to restore the means to operative position with respect to the detector, said controlling elements each being effective to act on the device after a predetermined number of beats of the loom only.

11. In a multi-color weft replenishing loom having a series of shuttles any one of which may become active and having also a transerrer arm movable on every detecting beat of the loom toward the weft supply, a weft detector mounted on the transerrer arm and movable therewith toward the weft supply of each shuttle, an actuator to be operatively connected to the detector as the latter approaches the weft supply and effective to move said detector against the weft supply, a device to render said actuator inoperative to act on the detector when a relatively large amount of weft is present, and mechanism to act on said device to cause the same to restore the actuator to operative relationship with respect to the detector whenever the active shuttle changes.

In testimony whereof I have hereunto affixed my signature.

HAROLD L. BLANCHARD.
